BUILDING BLOCK

Gerald L. Jonas, 66 Kirkland St.,
Cambridge, Mass. 02138

Filed Feb. 13, 1967, Ser. No. 5,783

Term of patent 14 years

(Cl. D18—2)

FIG. 1

FIG. 2

FIG. 3

FIG. 4

I claim:

The ornamental design for a building block, as shown.
